UNITED STATES PATENT OFFICE.

WALTER CHRISTOPHER, OF PHILADELPHIA, PENNSYLVANIA, ASSIGNOR
OF ONE-HALF TO WILLIAM GULAGER, OF SAME PLACE.

COLLAR.

SPECIFICATION forming part of Letters Patent No. 267,494, dated November 14, 1882.

Application filed August 7, 1882. (No model.)

To all whom it may concern:

Be it known that I, WALTER CHRISTOPHER, a citizen of the United States, and a resident of Philadelphia, Pennsylvania, have invented 5 an Improvement in Shirt-Collar Retainers, of which the following is a specification.

The object of my invention is to overcome the annoyance caused by the rising of the band of a shirt-collar above the neckband of 10 the shirt, and this object I attain in the manner which I will now proceed to describe, reference being had to the accompanying drawings, in which—

Figure 1 is a view of the neck of a shirt 15 with collar, one end of the latter being left unfastened to illustrate my invention; and Fig. 2, a view of a collar made according to my invention.

Ordinary shirt-collars, especially when rather 20 tight-fitting, have a tendency to rise in front under the influence of various movements of the body until the band of the collar is above the neckband of the shirt—a position which is both uncomfortable and embarrassing to the 25 wearer.

In carrying out my invention with the view 30 of overcoming this objection I form on the lower edge of the collar-band *a*, at a point adjacent to each of the front ends of the collar, 35 a tab, *b*, and on the neckband *d* of the shirt

I form tabs *e*, in such positions that they will coincide with the tabs *b* of the collar when the latter is applied to the shirt. Before the collar is applied the tabs *b* are turned up against 35 the inside of said collar and the tabs *e* are turned down against the neckband *d* of the shirt, and before buttoning the collar to the

front button, *f*, the tabs *b* are slipped under the tabs *e*, this engagement of the two sets of tabs preventing the objectionable rising of the 40 collar above alluded to.

I have shown my invention as applied to a standing collar; but it may be applied to turn-down collars as well, and in some cases the band of the collar may have slits for the reception of the tabs *e* on the neckband of the shirt, instead of being provided with tabs *b* for engagement with said tabs *e*. The construction shown is preferred, however, as the collar can be adjusted more readily in this case than 50 when slits are formed therein.

I am aware that collars have been furnished with tabs for holding neckties thereon, and I do not therefore claim broadly a collar having retaining-tabs; but

55 I claim as my invention—

1. The combination of the neckband of a shirt, having tabs *e* on each side of the central button, with a collar constructed for engagement with said tabs, whereby the rising of the 60 collar-band above the neckband of the shirt is prevented, as set forth.

2. The combination of the neckband *d* of the shirt, having tabs *e* on each side of the central button, *f*, with a collar, the band *a* of which 65 has tabs *b*, adapted to engage with the tabs *e*, as set forth.

In testimony whereof I have signed my name to this specification in the presence of two subscribing witnesses.

WALTER CHRISTOPHER.
